UNITED STATES PATENT OFFICE.

GEORGE W. WEAVER, OF NEW YORK, N. Y.

HAIR-WAVER.

1,369,994.

Specification of Letters Patent.

Patented Mar. 1, 1921.

Application filed August 23, 1917. Serial No. 187,877.

To all whom it may concern:

Be it known that I, GEORGE W. WEAVER, a citizen of the United States, residing at New York, in the county and State of New York, have made a certain new and useful Invention in Hair-Wavers, of which the following is a specification.

The invention relates to hair wavers.

The object of the invention is to provide 10 a new and improved hair waver which is simple and durable in construction and effective in operation.

A further object of the invention is to provide a hair waver in which a longer or 15 shorter wave in the hair may be obtained as desired by the user.

A further object of the invention is to provide a hair waver which is sanitary and does not injure the hair in use.

20 Further objects of the invention will appear more fully hereinafter.

The invention consists substantially in the construction, combination, location and relative arrangement of parts, all as will be 25 more fully hereinafter set forth as shown by the accompanying drawing, and finally pointed out by the appended claim.

Referring to the drawing, and to the figures contained therein:

30 Figure 1 is an elevation of hair waver embodying my invention, the same being represented partly in vertical section.

Fig. 2 is a sectional view of same taken on the line 2—2, Fig. 1, and looking in the 35 direction of the arrows.

The same part is designated by the same reference number wherever it occurs throughout the several views.

In accordance with my invention, I provide 40 two independent short sections of flexible non-elastic strands 1 and 2, which are suitably covered by any desired material such as rubber or the like designated at 3. These independent strands are then twisted

45 together so as to form longitudinal extending spiral ridges and valleys as shown in Fig. 1. After the two strands are twisted together an outside cover 4 is woven over or otherwise applied thereto as clearly 50 shown. This outside cover or stocking may be of any desired material, such as braided thread and is woven or applied thereon with sufficient looseness to permit the two enclosed strands to be twisted to form variable

spirals according to the length of wave to 55 be produced in the hair.

The adjacent ends of the two twisted strands are then covered with a non-metallic and water-proof material, indicated at 5. One method which I have found efficient for 60 accomplishing this, but to which method I do not desire to have my invention restricted is to dip the ends of the twisted strands into a water-proofing solution, and then allowing the same to harden thereon. In 65 this way, the end coverings also are applied over the stocking or covering which is common to both strands, thereby retaining the ends of the independent strands secured together side by side and avoiding the objection of forming an enlarged lump which 70 would result if a single strand was doubled over itself.

From the foregoing it will be seen that I provide a hair waver with longitudinal extending spiral ridges and valleys therein and that when a damped strand of hair is wound around the same and allowed to remain for a short while, there will be produced 75 a wave in the hair.

It will also be noted that the length of the wave to be imparted to the hair may be varied by simply twisting, more or less, the ends of the hair waver, thereby varying the pitch of the spiral ridges and valleys formed 80 by the twisted strands.

It will further be observed that the novel manner of covering the twisted strands by a covering common to both of them, after they have been twisted together provides a 85 smooth exterior surface throughout the entire length of the waver and prevents the loading and accumulation of dust or dirt in the crevices between the twisted strands, thereby overcoming the objections of hair 90 wavers which employ merely a covered wire doubled back upon itself and then twisted together to produce a variable spiral.

A further advantage obtained in my invention over prior devices of this character 100 is the manner of covering the end of the twisted strand. By the method employed in my invention the end of the strands are efficiently protected so as to prevent them from catching in, breaking or injuring the 105 hair.

To use the device, a strand of hair, slightly damped, is wound around the de-

vice. The ends of the device are then bent over to maintain the hair in position thereon. After a short period the device is removed from the strand of hair which, when 5 combed out, contains a wave therein.

Having thus described the objects and nature of my invention, what I claim as new and useful and desire to secure by Letters Patent is:—

10 A hair waver, comprising two independent flexible non-elastic strands twisted together to form a spiral, a single covering

applied over said assembled strands to retain the same in their twisted position relative to each other, and to allow the pitch of 15 the spiral to be varied, and an end covering applied over the ends of the strands to bind the same together substantially as shown and described.

In testimony whereof I have hereunto set 20 my hand on this 20th day of August A. D., 1917.

GEORGE W. WEAVER.
